BATTERY CONNECTER

Edward A. Lienhart and Orvin Ravnaas,
Ruso, N. Dak.

Application July 17, 1935, Serial No. 31,903

2 Claims. (Cl. 173—324)

Our invention relates generally to means for connecting conductors such as wires and cables to different types of electric batteries, such as storage batteries, air cells, dry cells, and particularly to a single connector which is arranged to be capable of being efficiently connected to the different types and sizes of terminals of different classes and types of batteries; and an important object of our invention is to provide a simple and efficient device of this character which can be manufactured very cheaply.

Another important object of our invention is to provide a device of the character indicated which can be very quickly and easily applied and removed from the battery terminal and so as to make an efficient electrical connection therewith.

Other important objects of our invention will be apparent from a reading of the following description in connection with the drawing, wherefore in for purposes of illustration we have shown a preferred embodiment of our invention.

In the drawing:

Figure 1 is a side elevational view of a portion of a storage battery of the size which is used in an automobile and showing the device of the invention connected to a terminal thereof.

Figure 2 is a top plan view of the device.

Figure 3 is a longitudinal vertical sectional view taken through Figure 2 approximately on the line 3—3.

Figure 4 is a transverse vertical sectional view taken through Figure 2 approximately on the line 4—4.

Referring in detail to the drawing, the numeral 5 generally designates the device of the invention which includes the tapering base 6 in the form of a flat metal plate having in its wide end a hole 7 of sufficient size to receive the battery terminal 8 of the storage battery 9. In the middle of the top of the plate 7 is a sliding latch 10 which slides in inverted L-shaped guides 11 and 12, toward and away from a hole 13 which is formed through the plate 6 to receive the smaller terminals of the small storage batteries and dry cells. The end of the latch 10 remote from the hole 13 has two upstanding lugs 14 acting as handles for retracting the slide against the action of the spring 15 which has one end coiled about a lug 16 on the end of the latch 10 and about an L-shaped standard 17 at its oppo-

site end, the standard 17 rising from the top of the base as clearly shown in Figure 3. It is obvious that when a terminal has been entered in the hole 13 and the latch 10 released the sharp edge of the latch will engage the terminal and push the same against the opposite side of the hole 13 and thereby firmly electrically engage the terminal and hold the plate 6 thereto.

At the small end of the plate 6 is a hole 18 which receives the bolt 19 which includes a binding post 20 for connecting a cable 21 in the manner indicated in Figure 1. The bolt has below and engaging the bottom of the plate 6 the head 22 to which the upper end of a helical expanding spring 23 is connected, the said spring having its lower end connected to a second head 24 which is adapted to rest on the top of the battery as indicated in Figure 1.

It is obvious that when the plate 6 has been applied to the large battery terminal as shown in Figure 1, the spring 23 being compressed in the act, upon release of the plate 6 the same will swing upwardly under the impetus of the spring 23 so that the edges of the opening 7 will dig into the sides of the battery terminal 8 and thereby make a firm electrical connection. Simply depressing the small end of the plate 6 and putting the plate 6 back into a horizontal plane will permit releasing the edges of the opening 7 from the battery terminal 8.

Although I have shown and described herein a preferred embodiment of my invention, it is to be definitely understood that I do not desire to limit the application of the invention thereto, and any change or changes may be made in the materials, and in the structure and arrangement of the parts within the spirit of the invention and scope of the subjoined claims.

Having thus described the invention, what we claim as new is:

1. A battery connector of the character described, comprising an elongated plate provided with an opening in one end portion thereof completely enclosed by the material of the plate for receiving a battery post, said plate being provided with a depending coil spring at the opposite end thereof adapted to engage the top of a battery at its lower end to tilt the plate when the post of a battery is disposed through the opening so that the edge portions of the plate at the open-

ing will bite into the post and means on the plate whereby a conductor wire can be connected thereto.

2. A battery connector of the character described comprising an elongated plate provided with an opening in one end portion thereof completely enclosed by the material of the plate, said plate being provided with a depending coil spring at the opposite end thereof adapted to engage the 10 top of a battery at its lower end to tilt the plate

when the post of a battery is disposed through the opening so that the edge portions of the plate at the opening will bite into the post, said last mentioned end of the plate having a binding post disposed therethrough and to which the spring 5 is secured, said binding post being provided with a nut thereon whereby a conductor can be clamped between the nut and the plate.

EDWARD A. LIENHART.

ORVIN RAVNAAS.
